UNITED STATES PATENT OFFICE

PAUL CRICCHIO, OF NEW YORK, N. Y., ASSIGNOR TO WROUGHT IRON & ART GLASS FIXTURE CO., INC., OF NEW YORK, N. Y.

DESIGN FOR A TABLE LAMP OR ARTICLE OF SIMILAR NATURE

Application filed February 15, 1930. Serial No. 34,560. Term of patent 3½ years.

To all whom it may concern:

Be it known that I, PAUL CRICCHIO, a citizen of the United States, residing in New York city, in the county of New York and State of New York, have invented a new, original, and ornamental Design for a Table Lamp or Article of Similar Nature, of which the following is a specification, reference being had to the accompanying drawing, forming a part thereof.

The figure is a perspective view of a table lamp or article of similar nature showing my new design.

The rear side of the lamp is in all respects similar to the front side as shown.

I claim:

The ornamental design for a table lamp or article of similar nature, as shown and described.

In testimony whereof I affix my signature.

PAUL CRICCHIO.
